Inventor:

By his Attorney, Leo. McNamee

UNITED STATES PATENT OFFICE.

LEO J. GRUBMAN, OF NEW YORK, N. Y., ASSIGNOR, BY MESNE ASSIGNMENTS, TO VOICES, INCORPORATED, A CORPORATION OF DELAWARE.

ARTICULATIVE SOUND-PRODUCING DEVICE FOR DOLLS, ETC.

Application filed March 11, 1922. Serial No. 542,884.

This invention relates to sound producing devices for toys, and more particularly to what are now commonly referred to in the art as talking dolls, said device being provided with means for producing sound and effecting an articulated emission thereof simulating the pronunciation of word syllables by the human voice.

It is the primary object and purpose of my invention to provide such a device wherein the several operative parts for producing and effecting an interrupted articulated emission of the sound are wholly contained and at all times operate within a chamber or casing of relatively limited dimensions so that it becomes possible to utilize such a device and mount the same within the bodies of small sized dolls for retail sale at comparatively low cost.

More particularly, my invention comprehends such a sound producing and articulating device of the gravity automatic type as distinguished from the manually operable construction having a spring sustained air expelling member.

In a practical embodiment of my present improvements, I provide within the outer casing an axially positioned fixed guide and a gravity movable weight supported by and slidable along said guide together with the sound producing element and means whereby the sliding movement of the weight along the guide will produce an interrupted sounding of said sound producing element.

With the above and other objects in view, the invention consists in the improved articulative sound producing device and in the form, construction and relative arrangement of its several parts as will be hereinafter more fully described, illustrated in the accompanying drawings and subsequently incorporated in the subjoined claims.

In the accompanying drawings,

Fig. 1, is a side elevation of my improved sound-producing device;

Fig. 2, is an elevation of one end thereof;

Fig. 3, is an elevation of the opposite end thereof;

Fig. 4, is a central sectional elevation taken upon plane of line 4—4, Fig. 2, showing the bellows collapsed;

Fig. 5, is a similar view, with the device in reversed position as related to Fig. 4, and with the bellows expanded;

Fig. 6, is a view of the outer face of the bellows actuating weight;

Fig. 7, is a view of the inner side of one end disc of the casing;

Fig. 8, is a view of the inner side of the other or perforated end disc of the casing;

Fig. 9, is a view of the inner face of the bellows base diaphragm;

Fig. 10, is a side or edge elevation of the bellows weight;

Fig. 11, is an elevation of the sound box or tube;

Fig. 12, is an end elevation of said tube;

Fig. 13, is a central section of the device reversed as related to Fig. 5, with the operative parts positioned preparatory to the collapse of the bellows;

Fig. 14, is a transverse section taken upon plane of line 14—14, Fig. 13.

In the embodiment of the device which I have selected for purposes of illustration, I provide a cylindrical shell or casing *c* which may be produced of heavy cardboard, sheet metal or other suitable material. At one of its ends, this casing is closed by a disc or cap *c'* and at its other end by a similar disc or cap *c''*. These closure discs are preferably, though not necessarily, in the form of sheet metal stampings, each provided at its outer edge with an angularly disposed flange for frictional engagement with the respective ends of the casing or shell wall. It will be observed that this casing provides an unobstructed chamber, the axial or longitudinal dimension of which is substantially equal to its diameter. It is not, however, an essential requisite of the invention that said casing or chamber shall be of cylindrical form as it will become obvious as this description proceeds that in so far as the effective operation of the device is concerned, said casing or chamber may be of various other shapes.

One wall of the casing above described is provided with one or more sound outlet or emission apertures. Preferably, I provide such apertures as indicated at *c³* in the end cap or disc *c'* of the casing. If de-

sired, however, these apertures can be provided in the body wall of the shell or cylindrical casing *c*.

Within the casing and extending axially or longitudinally of the chamber formed thereby there is arranged a fixed guide. As herein shown, this guide is in the form of a tube *a*, which, as will hereinafter appear, likewise functions as a sound receiving 10 chamber. This fixed guide provides a support for the freely slideable head *b* of the bellows which is generally indicated at *B*. Preferably, though not necessarily, the bellows head *b* is concentrically related to the 15 fixed guide tube *a* and the wall of the casing *c* and is movable along said tube from a position at one end of the casing chamber within which the bellows is enclosed to a position substantially at the opposite end 20 thereof.

In the present disclosure, I have shown a simple means for fixedly securing the guide tube *a* in place and to this end, I provide the casing end disc or cap *c'* centrally there- 25 of with an inwardly projected portion *c''* which is adapted to be received within one end of the tubular post or guide. The other end of this tubular guide is provided at diametrically opposite points with the longi- 30 tudinally projecting lugs *a'* for engagement in suitably formed recesses *b'* provided in a part of the other bellows head *b''* which is suitably fixed to the inner side of the end disc or cap *c''* of the casing. The projecting 35 lugs *a'* are of such length that between these lugs and the bellows head *b''*, the ports *a''* are produced which afford communication between the interior of the tubular post *a* and the interior of the bellows *B* through 40 which the air may freely enter into the bellows or be expelled therefrom.

Adjacent to its other end the wall of the tubular post *a* is provided with a sound emission slot or opening *a''* and through 45 which air is also drawn into the bellows in the movement of the head *b* in one direction.

The bellows head *b* is moved under the force of gravity to collapse or distend the bellows, and for this purpose I provide a 50 weight *S* suitably fixed or attached to the outer side of the head *b*. However, if desired, the head *b* and the weight *S* may be formed in a single one piece structure. The 55 weight *S* is provided with a central opening *s* loosely receiving the fixed guide post *a* so that said weight may freely slide without binding along said post in either direction. In one side thereof the weight *S* is provided 60 with a sound outlet opening *s'*, the inner end of which is adapted to register with the emission slot or opening *a''* in the wall of the fixed guide tube in the sliding movement of said weight along the tube. The two bel-

lows heads *b* and *b''* are connected at their marginal edges with the opposite ends of the flexible collapsible tubular wall *b''*. This flexible wall may be produced from rubberized cloth or other suitable material.

Within the fixed tubular post *a* the sound 70 producing reed *r* is mounted or supported in any suitable manner adjacent to the ports *a''*.

In the operation of the device above described, assuming that the parts are in the relative positions shown in Fig. 5 of the drawings, upon the reversal of the device, the weight *S* and bellows head *b* slide by gravity along the fixed post *a* from one end of the casing chamber to the other. Initially 80 in this sliding movement and before the opening *s'* of the weight is in registering relation with the slot *a''* in the wall of the guide post, there is a slight emission of sound produced by reed *r* in the initial expulsion 85 of the air through said reed, such sound waves passing through slot *a''* and between the wall of the tube and the wall of the opening *s* in the weight and hence through the opening *s'*. This initial emission of sound in small volume simulates the sound of the letter "M". The sounding of the letter "a" immediately follows by the emission of sound from the interior of the fixed tube *a* in larger volume through the slot *a''* and the opening *s'* of the weight which is now in 90 registering relation with said slot. As the opening *s'* moves out of registering relation with the slot *a''* to a position below the same, the sound waves from the interior of the tube again pass in reduced volume between the wall of the tube and the weight *S* through the opening *s'*, again simulating the letter "M" and when the weight *s'* moves entirely below the slot *a''*, the sound again 100 issues through said slot in maximum volume which continues until the weighted head of the bellows reaches its final position of rest as shown in Fig. 4 of the drawings and during which time the sounding of the letter "a" is simulated. In this manner, the successive pronunciation of the two syllables of the infant cry "ma-ma" are realistically 105 simulated.

When the device is again inverted from the position in Fig. 4, the bellows is expanded by the sliding movement of the weight *S* to the opposite end of the casing chamber and air enters the bellows through the slot *a''* and the ports *a''* of the tubular post *a*.

From the above description, it will be seen that the operative parts of the device both for producing and articulating the sound are at all times wholly contained within the chamber of the external protecting casing and by the elimination of protuberant or extraneous elements, it be-

comes possible to utilize such devices in dolls or toys of comparatively small size.

In this connection, I herein use the term "self-contained" as indicative of the fact 5 that the enclosure of the operative parts is complete, there being no protuberant parts, and no extraneous manipulation other than that involved in changing the inclination of the device to effect the otherwise automatic action of the gravity-valve slide 10 member S, as hereinbefore set forth.

The device is not only simple and inexpensive of structure, but is also practically indestructible and fool-proof under ordinary 15 conditions of use, since it is not subjected to extraneous pressure, and is essentially automatic in operation to all intents and purposes.

Furthermore, it is to be noted that the 20 only movable part in my device, relatively speaking, other than the flexible sides of the bellows, is the bellows head b, and its integrally attached slide-valve-weight S, reciprocally mounted on the rigid guide tube 25 a, which latter is also an important economic factor in structure in that it functions as air compression chamber, reed container, and guide and lateral support for the member S, at the same time stiffening and reinforcing 30 the end discs of the casing.

What I claim as my invention and desire to secure by Letters Patent is,

1. A casing providing a chamber unobstructed longitudinally of the casing, a 35 sounding reed, a part movable longitudinally in said chamber to cause the passage of air through said reed, a relatively fixed member in said chamber, and said member and said part having means cooperating in 40 the movement of said part to interrupt the emission of sound produced by said reed.

2. A sound producing device comprising an air chamber, a rectilinearly movable member adapted to compress the air in said 45 chamber, and means guiding said member in its movement, a sound producing element operated by passage of air therethrough in the movement of said member, and said member and the guiding means having co- 50 acting parts to interrupt the emission of sound produced by said element.

3. A sound producing device comprising an air chamber, a rectilinearly movable member adapted to compress the air in said 55 chamber, a sound producing element operated by the compressed air, a relatively fixed guide for said member, said guide and said member having cooperating means to interrupt the emission of sound produced by 60 said element.

4. A sound producing device comprising an air chamber, a reciprocal member for 65 expelling air from said chamber, a sound producing reed through which the air is expelled, a guide for said member, and said

guide and member having cooperating means to interrupt the emission of sound produced by said element.

5. In a sound producing device, a casing, a post arranged longitudinally within the 70 casing and supported in fixed relation thereto, a sound producing element, and means for effecting an interrupted sounding of the sound producing element including a member slideable along said post within and 75 relative to the casing.

6. In a sound producing device, a casing, 80 guide means arranged longitudinally within the casing and supported in fixed relation thereto, a sound producing element, and means for effecting an interrupted sounding of the sound producing element including a member supported by said guide means and slideable therealong within and relative to the casing.

7. In a sound producing device, a casing, a post axially positioned within said casing and supported upon one of the casing ends in fixed relation to the casing, a sound producing element, and means for effecting an 85 interrupted sounding of the sound producing element including a member supported by said post and slideable by gravity therealong within and relative to the casing.

8. In a sound producing device, an air 90 compression chamber having a movable head at one end thereof, a sound producing element, a relatively fixed member supporting said movable chamber head, and said chamber head and said supporting member having means cooperative with each other in the movement of said chamber head to effect an interrupted emission of the sound produced by said sound producing element.

9. In a sound producing device, an air 95 compression chamber having a movable head at one end, a sound producing element, guiding and supporting means for said movable chamber head, an enclosing casing for said mechanism having means on one wall thereof sustaining said guiding and supporting means in a relatively fixed position, and said casing having an opening in one wall for the emission of sound, and said movable chamber head and the guiding and supporting means having parts cooperating in the movement of said head to effect an 100 interrupted emission of the sound produced by said sound producing element.

10. A sounding device comprising a protecting casing, a post arranged axially within the casing supported by having its opposite ends engaging the end walls of the casing, a weight supported by and mounted upon 105 said post freely slideable therealong within and relative to the casing, a sound producing element, and means whereby sliding movement of the weight along the post will produce interrupted sounding of the sound producing element.

11. A sounding device comprising a bellows having a moveable head, a sound producing element, a post, and means cooperative between the post and the moveable head whereby to interrupt the sound produced by the sound producing element during movement of the head, said bellows comprising also a second head, a tubular member extending between said heads being fixed by its circumferential end portions to the marginal parts of said heads, said tubular member being formed of soft flexible material whereby to permit the moveable head to move freely toward and away from the second head, a weight comprised in the moveable head operable in one position of the device to move said moveable head by gravity for expelling air from the bellows, and said moveable head having an opening therethru to slideably receive said post whereby the post constitutes a mounting upon which said moveable head is slideably supported and guided.

12. In a sound producing device, an air compression chamber having a movable head at one end, a sound producing element, a guide member for said head of the compression chamber along which said head is freely slideable, said head and guide member having cooperating means controlling the emission of sound produced by said sound producing element, and an enclosing casing for said mechanism provided with means for supporting said guide member in a relatively fixed position.

13. In a sound producing device, a tubular bellows having a fixed head at one end thereof and a gravity movable head at its opposite end, a sound producing element, relatively fixed supporting and guiding means for the movable bellows head, and said latter means and the movable bellows head having cooperating parts controlling the emission of sound produced by said sound producing element in the movement of said bellows head in one direction.

14. In a sound producing device, a tubular bellows having a fixed head at one end and a gravity movable head at its opposite end, a sound producing element, a relatively fixed guide for said movable bellows head supported upon the fixed head of the bellows and extending through the bellows chamber,

and said guide and the movable bellows head having cooperating means controlling the emission of the sound produced by said sound producing element in the movement of the bellows head in one direction. 55

15. In a sound producing device, a tubular bellows having a fixed head at one end and a gravity movable head at its opposite end, a member supported in a relatively fixed position upon the fixed head of the bellows and extending axially of the bellows chamber, a sound producing element, and said member and the movable bellows head having cooperating means controlling the emission of sound produced by said element in the movement of the bellows head in one direction. 70

16. In a sound producing device, a tubular bellows having a fixed head at one end and a gravity movable head at the opposite end thereof, a tubular guide post for the movable bellows head supported against axial movement and in communication with the bellows chamber, a sound producing reed mounted within said post, and said post and the movable bellows head having means cooperating in the movement of said head in 80 one direction to control the emission of sound produced by said reed. 75

17. In a sound producing device, an air compression chamber, a movable member for expelling air under pressure from said chamber, a sound receiving chamber having an emission opening for the sound and a wall of said chamber constituting a support for said member and prescribing the path of its air expelling movement, and a sounding reed through which the air is expelled from said compression chamber into the sound receiving chamber in the movement of said movable member in one direction. 85 90

18. In a sound producing device, an air chamber, a sounding reed, a rectilinearly movable member constituting one end of the air chamber and operable to cause the passage of air through said reed, and a sound receiving chamber having an emission opening for the sound, and a wall of said chamber constituting a support for said member and prescribing the path of its rectilinear movement. 100

LEO J. GRUBMAN.
